UNITED STATES PATENT OFFICE.

CHARLES LEE FITCHET, OF SAN FRANCISCO, CALIFORNIA.

MIRROR STRUCTURE.

1,422,685.

Specification of Letters Patent. Patented July 11, 1922.

Application filed June 5, 1920. Serial No. 386,727.

To all whom it may concern:

Be it known that I, CHARLES LEE FITCHET, a citizen of the United States of America, and resident of San Francisco, county of 5 San Francisco, and State of California, have invented certain new and useful Improvements in Mirror Structures, of which the following is a specification.

This invention relates broadly to dressing 10 room furniture, and more especially to a mirror structure which is particularly adapted for use in ladies' dressing rooms, boudoirs, and the like as a toilet furnishing, and which is also adapted to be employed for 15 various decorative purposes.

The primary object of the invention is to provide a mirror structure which, while adapted for a variety of uses, is primarily designed for the purposes to which dressing 20 tables and stands have heretofore been applied, and which embodies a plurality of mirrors which may be adjusted relatively both with respect to each other and to the position occupied by the user, enabling the 25 user to obtain by reflection views of his person not conveniently obtainable by the use of mirror arrangements heretofore provided in dressing tables or other dressing-room furniture.

30 A further object is to provide, in a device of the character mentioned, a mirror-supporting frame having a truck or carriage which is arranged for travel in a trackway either of straight or arcuately curved form, 35 which automatically adjusts itself to the form of the trackway which it follows, which is conveniently shiftable to any desired position on said trackway with the exercise of a minimum of force or effort, 40 and which at all times maintains the mirror-frame in rigid upright position.

With these and other important objects in view, the invention resides in the features of construction, arrangement of parts and 45 combinations of elements which will hereinafter be exemplified, reference being had to the accompanying drawings, in which—

Figure 1 is a perspective view of the invention;

50 Figure 2 is an enlarged under side elevation of the carriage structure;

Figure 3 is a central longitudinal section of the same disposed in operative position in its trackway;

55 Figure 4 is a transverse section on line 4—4, Fig. 3;

Figure 5 is an enlarged sectional elevation of one of the pivotal connections between a mirror and its support;

Figure 6 is a diagrammatic view illustrating the purpose of the curvatures provided in the trackways; and—

Figure 7 is a section on line 7—7, Fig. 5.

Referring to said drawings, in which like designating characters distinguish like parts throughout the several views—

1 indicates the side rails and 2 the transverse connecting rail of a horizontally disposed frame which has an approximately rectangular form and which is supported at 70 an appropriate height by suitable legs 3. Each of the rails 1 and 2 is preferably made of rectangular cross-sectional form, as is most clearly shown in Fig. 4. Extending throughout approximately the entire length 75 of each rail 1, but terminating adjacent to each of the ends thereof, is a channel 7, and fitted for travel in said channel is a carriage upon which is mounted a support 8 of substantially U-shape for a mirror 9, said rail 80 thus constituting a trackway for said carriage. Extending likewise throughout the length of the transverse rail 2 is a channel 5 having fitted for travel therein a carriage upon which is mounted a support 4 for a 85 mirror 6, said rail 2 likewise constituting a trackway.

Provided in each of the inner side walls of each trackway, that is, located laterally of the channel thereof, is one or more longitudinal grooves 10, two such grooves separated by a tongue 11 being shown in the drawings. Said grooves are designed for the reception of the ends of rollers 12 which form parts of the carriage. Said carriage comprises a 90 pair of pivotally related truck bodies 13 and 14, the truck body 13 having a tongue 13^a disposed in underlying relation to a tongue 14^a formed on the truck body 14, the truck body 13 having therein a channel 15 in which 100 said tongue 14^a is received. Received in registering holes provided in the tongues 13^a and 14^a is a vertical centrally disposed pivot pin 16 which has its upper end extending upward between the upper portions of the 105 bodies 13 and 14 and lying flush with the top surfaces of the latter. Said pivot pin has its lower end provided with an external flange 16^a seated in underlying relation to the tongue 13^a and is supported by screws 17 directed into its upper end through a plate 18. Mounted upon said plate and attached 110

- thereto by means of screws 19 is a saddle 20 having a hole 21 extending longitudinally therethrough and in which is rigidly supported the central part of the horizontal portion of the U-shaped mirror support which may be either the support 4 or the support 8. The elevation of the plate 18 is such that its under surface is adapted to ride upon the top surface of the rail upon which it travels.
- 10 Carried by the outer end of each of the truck bodies 13 and 14 are two pairs of angular arms 22 in which are journaled the ends of the rollers 12, said arms being so disposed that they, with the ends of the rollers, are received by the grooves 10 of the trackway, as shown in Figs. 3 and 4. The lower rollers are adapted for travel upon the surface at the bottom of the channel 5 or 7, as the case may be, while the upper rollers travel upon the tongues 11 and occupy positions in closely underlying relation to the inwardly directed flanges 1^a of the rail 1 or the flanges of the rail 2, as the case may be.
- 15 The purpose had in view in forming the carriages which operate on the trackways 1 with the pivotally connected trucks is to render the same sufficiently flexible to follow the curvatures of the outer ends of the trackways without the tendency to bind which would otherwise prevail in a carriage having the length requisite to prevent lengthwise rocking movement with respect to the trackway. The carriage which operates on the straight trackway 2 preferably has the flexible structure described, but might have the trucks rigidly connected. Another object of the pivotal arrangement described is to permit the mirror supports 4 and 8 to be rotated as required to cause the mirrors to face in any desired directions. As is obvious, the saddle 20, the plate 18, and the pivot-pin 16 may together be rotated freely with respect to the other parts of the carriage, so that the mirror 6 or 9, as the case may be, may be readily disposed at any angle to the line of the trackway on which it travels.
- 20 The channels 7 of the trackways 1 are prolonged at their inner, or rear, ends past the ends of the trackway 2 a distance sufficient to allow the carriages to assume positions wherein the mirrors 9, or either of them, may be positioned in direct alinement with the mirror 6, as indicated in dotted lines in Fig. 1.
- 25 Each of the mirrors 6 and 9 comprises a frame 23, herein shown as of rectangular metal-rod form, a mirror glass 24 having a backing 25 of suitable material, preferably of an ornamental character, an edge-encasing sheath or border 26 of sheet metal or other appropriate thin material, and supporting clips 27; said clips being rigidly mounted upon the frame 23 at suitably spaced intervals and each having its inner end channeled for the reception of the ad-

jacent portion of the sheath 26, the opposing jaws formed by the channel in the clip being disposed in tight-gripping relation to said sheath.

Rigidly mounted upon each of the upright side members of the frame 23 substantially midway between the ends of the latter is a clip 28 which is similar in form to, but preferably of greater width than, the clips 27 and which has formed integral therewith a trunnion 29. Said trunnion is supported by the projecting lip 30^a of the lower section 30 of a bearing which is adjustable on the adjacent upright member of the U-shaped support 4 or 8, as the case may be. Also adjustable with respect to the section 30 is an upper bearing section 31 having a lip 31^a which overlies said trunnion 29. By adjustment of the upper section 31 any desired frictional grip may be secured on said trunnion for regulating the resistance offered to swinging movement of the supported mirror. A collar 34 formed on the end of each trunnion 29 is received in companion grooves 35 provided in the bearing sections, as shown in Figs. 5 and 7.

As hereinbefore stated, the outer ends of the trackways 1 are arcuately curved. The curvature is in an inward direction, as shown, and is designed to permit the mirrors 9 to be moved to positions in which they will directly cooperate with the mirror 6, when the latter occupies a position in which it is approximately centered on its trackway 2, for reflecting images from one to the other thereof, as is indicated in broken lines in Fig. 6.

The frame constituted by the track rails 1 and the track rail 2 forms a partial enclosure within the confines of which the user may stand or occupy a chair while dressing or arranging the toilet. Since each of the mirrors 6 and 9 may be moved laterally along its trackway to any desired position, may be rotated to any desired angle with respect to the line of its trackway, and may be swung on its pivotal mounting to any desired angle with respect to the vertical, it is apparent that the user may obtain practically any desired view of his person readily and with a minimum of effort.

While the mirror 6 is herein shown as movable along the trackway 2, it will be understood that it may be mounted stationarily.

Any suitable arrangement of lights may be provided whereby proper illumination may be had. For illustrative purposes only I have shown angular supporting standards 32 located at opposite sides of the mirror 6 and mounted on the rear side of the track rail 2, said standards being surmounted by lamps 33.

The structure herein described may of course be made in any size of any preferred

material and finish, and may be employed for any purpose to which it is applicable.

It will be noted that the various minor details of construction and arrangement herein shown and described are employed only for purposes of illustration and that I am therefore not to be understood as limiting myself to the precise details disclosed. On the contrary, I reserve the right to make any changes in the form, proportion and details of construction and arrangement of the parts which may fall within the scope of the appended claims.

What is claimed is—

15 1. A mirror structure comprising a frame formed to provide a partial enclosure for the person of the user, parts of said enclosing frame being shaped to form trackways, carriages movable along said trackways, each carriage having pivotally related trucks providing for free travel thereof throughout its trackway, each carriage embodying a part rotatable on a vertical axis, and a mirror carried by said rotatable part.

25 2. A mirror structure comprising a frame formed to provide a partial enclosure for the person of the user, parts of said enclosing frame being shaped to form trackways having curved portions, carriages movable along said trackways, each carriage having pivotally related trucks providing for free travel thereof throughout its trackway, each carriage embodying a part rotatable on a vertical axis, a mirror support carried by said rotatable part, and a mirror carried by said support, said mirror having a horizontal axis upon which it is rotatable.

35 3. A mirror structure comprising a frame of approximately rectangular form having one side open, said frame forming a partial enclosure for the person of the user, the three sides of said frame being formed to provide trackways, carriages embodying complementary trucks arranged for travel along said trackways, each carriage embodying a part rotatable on a vertical axis, and a mirror carried by said rotatable part.

45 4. A mirror structure comprising a frame of approximately rectangular form having one side open, said frame forming a partial enclosure for the person of the user, the two opposite sides of said frame being formed to provide trackways having their outer ends arcuately curved, carriages having complementary pivotally connected end portions arranged for travel along said trackways, each carriage embodying a part rotatable on a vertical axis, and a mirror carried by said rotatable part, each of said mirrors being movable independently of all the others into a plane of any desired angle or inclination.

55 5. A mirror structure comprising a frame of approximately rectangular form having one side open, said frame forming a partial

enclosure for the person of the user, the two opposite sides of said frame being formed to provide trackways, and the third side forming a straight trackway, carriages embodying complementary pivotally connected trucks arranged for travel along said trackways, each carriage also including a part rotatable on a vertical axis, and a mirror carried by said rotatable part, said mirror being mounted for rotary movement on a horizontal axis.

6. A mirror structure comprising a frame of approximately rectangular form having one side open, said frame forming a partial enclosure for the person of the user, the two opposite sides of said frame being formed to provide trackways having their outer ends arcuately curved inwardly toward each other, the third side forming a straight trackway, carriages having complementary pivotally connected end portions arranged for travel along said trackways, each carriage embodying a part rotatable on a vertical axis, a mirror support carried by said rotatable part, and a mirror mounted on each of said supports and rotatable on a horizontal axis.

7. A mirror structure comprising a frame of approximately rectangular form having one side open, said frame forming a partial enclosure for the person of the user, the two opposite sides of said frame having their outer ends arcuately curved toward each other, each of said two opposite sides being channeled longitudinally to form trackways, a carriage arranged for travel in each of said trackways, said carriage embodying pivotally connected trucks adapting it for travel on the curved portion of its trackway, said carriage also including a part rotatable on a vertical axis, a mirror support carried by said rotatable part, a mirror mounted on said support, and a mirror mounted on the third side of said frame, each of said mirrors being arranged for swinging movement on a horizontal axis.

8. A mirror structure comprising a frame of approximately rectangular form having one side open, said frame forming a partial enclosure for the person of the user, the side of said frame opposite the open side being shaped to form a straight trackway, a frame arranged for travel on said trackway, a mirror carried by said frame, each of the other sides of said frame having their outer ends arcuately curved toward each other and being channeled longitudinally to form trackways, a carriage adapted for travel along each of the last mentioned trackways, said carriage being composed of complementary pivotally connected trucks adapted automatically to assume such positions with respect to each other as to conform to either the straight or the curved portion of its trackway when moved therealong, a mirror support mounted upon said carriage and

rotatable on a vertical axis, and a mirror carried by said support, the last mentioned trackways being prolonged at their inner ends to permit the carriages to assume positions in which the thereby carried mirrors may be alined with the first mentioned mirror.

9. A mirror structure comprising a frame of approximately rectangular form having one side open, said frame forming a partial enclosure for the person of the user, the side of said frame opposite the open side being channeled longitudinally to form a straight trackway, and the other sides of said frame having their outer ends arcuately curved toward each other and being channeled to form trackways, a carriage arranged for

travel along each of said trackways, said carriage having complementary pivotally connected end portions whereby it is rendered free to travel without binding, a mirror support mounted upon each carriage and rotatable on a vertical axis, and a mirror carried by said support, the trackways having curved portions being prolonged at their inner ends past the ends of the straight trackway.

In testimony whereof, I affix my signature in presence of two subscribing witnesses.

CHARLES LEE FITCHET.
